[57] CLAIM

The ornamental design for a cruet for vinegar, oil or the like, as shown and described.

DESCRIPTION

FIG. 1 is a perspective view of a cruet for vinegar oil or the like showing my new design;

FIG. 2 is a front elevational view thereof;

FIG. 3 is a side elevational view thereof; and

FIG. 4 is a top view thereof.

The bottom is flat and unornamented.
